UNITED STATES PATENT OFFICE.

GEORGE E. ADAMS, OF NEW BRITAIN, CONNECTICUT.

DESIGN FOR A STUD MEMBER FOR DETACHABLE FASTENERS.

SPECIFICATION forming part of Design No. 28,917, dated June 28, 1898.

Application filed May 27, 1898. Serial No. 681,953. Term of patent 31 years.

To all whom it may concern:

Be it known that I, GEORGE E. ADAMS, a citizen of the United States, residing at New Britain, in the county of Hartford and State of Connecticut, have invented and produced a new and original Design for the Stud Member of Detachable Fasteners, of which the following is a specification, reference being had to the accompanying drawings, forming 10 a part thereof.

In the drawings, Figure 1 is a plan view of a stud member of a detachable fastener embodying my improved design. Fig. 2 is a cross-sectional view on the line *x-x*, Fig. 1. Fig. 3 is 15 a perspective view.

As shown in the drawings, the leading or material feature in my present design consists

of the rim or edge A, with inwardly extending arms B converging toward a common center and terminating at their inner ends in upwardly-extending sections C of a dome, constituting the stud portion of the member. The sections of the dome or stud proper are slightly separated, giving the same a split appearance. 20

Having thus described my invention, what I claim as new is—

The design for a stud member of a detachable fastener herein shown and described. 25

GEORGE E. ADAMS.
